C. PHELPS

SECTION FOR STEAM AND HOT WATER FURNACES

Filed August 10, 1922

Inventor
Charles Phelps
by Orwig C. Hague, Atty's.

UNITED STATES PATENT OFFICE.

CHARLES PHELPS, OF OSKALOOSA, IOWA.

SECTION FOR STEAM AND HOT-WATER FURNACES.

Application filed August 10, 1922. Serial No. 580,872.

My invention relates to improvements in hot water furnaces and steam boilers, such as used for heating buildings. The invention consists primarily in a single section 5 of a furnace, being one of a number in the same furnace, which are exactly alike and arranged to be bolted and secured in operative relation with each other to form a complete furnace, the size of which may be 10 varied by increasing or decreasing the number of sections, each section forming a water leg with communicating openings near its top and bottom so arranged that when two sections are bolted together, the two said sections will be in communication with each 15 other through said opening, the said sections being arranged so as to form the fire box and combustion chamber when secured together.

20 This invention more particularly relates to an improved section for boilers such as illustrated and described in my patents Number 1,203,044 issued October 31, 1916 and Number 1,278,379 issued September 10, 25 1916. The sectional members of these patents, and all other previous patents that I am aware of, have been joined together and placed in communication with each other by joints that have had to be machined or 30 otherwise expensively connected together.

Furthermore, I have found considerable difficulty in joining that portion of the edges of the sections which go to form the fire box and combustion chambers.

35 It is, therefore, the object of my invention to provide a boiler section so shaped and constructed that it may be formed of a single piece of cast metal having members so arranged that joints between the water communicating openings may be formed without expensive machinery, and also the joints between the fire box portion of the sections.

40 A further object is to provide an improved method for constructing a communicating passageway between adjacent sections of boilers whereby steam and water tight joints may be maintained, and whereby the cost of manufacture is materially reduced.

45 These and other objects will be apparent to those skilled in the art.

50 My invention consists in the construction, arrangement and combination of the various parts of the device, whereby the objects contemplated are attained, as hereinafter more 55 fully set forth, pointed out in my claims,

and illustrated in the accompanying drawings, in which:

Figure 1 is a front elevation of one of the sections of such a heater as above described.

Figure 2 is a side elevation of a number 60 of the sections placed together, in operative relation with each other, the front and back wall of the furnace being omitted, which forms no part of my present invention.

Figure 3 is a vertical, detail, sectional 65 view taken on the line 3—3 of Figure 1.

Figure 4 is a detail sectional view taken on the line 4—4 of Figure 1.

Figure 5 is a detail sectional view taken on the line 5—5 of Figure 1. 70

Figure 6 is a detail sectional view taken on the line 6—6 of Figure 2.

Referring to Figures 1 and 2 of the drawings, I have used the reference numeral 10 to indicate generally a single section of my 75 improved heater. Each of these sections comprises hollow and parallel leg members 11, the upper ends of which are connected by a head member 12, the said leg members being connected intermediate their ends by 80 a hollow cross member 13.

This member 13, as shown in section in Figure 5, comprises a top face member 14 which is provided with a U-shaped portion 15 in cross section formed integral therewith to form an opening 16, the width of the member 15 being less than the width of the member 14 so that a greater surface will be brought in contact with the heat from the fire box. The width of the members 14 90 is equal to the width of the legs 11, and they are flat on their top surface so that when a number of the sections are joined together, as illustrated in Figure 2, a comparatively tight floor will be formed thereby above the 95 members 15.

The legs 10, as shown in cross section in Figure 6, are constructed similar to the members 15, with the exception that the tubular members 17 are each provided with a face 100 plate 18 which is formed on the outside of the said tube 17 and each of said plates being provided with a laterally projecting portion 19 and 20, the projection or flange 19 being in line with the plate 18, while the 105 flange 20 is inclined inwardly so that when the two sections are joined together the flange 19 will overlap the flange 20, and so arranged that the openings or grooves 21 will be provided between the end of the 110

flange 20, and the inner face of the flange 18.

When the sections are assembled, the openings 21 are filled with asbestos or other heat-resisting cement, and the entire face of the plate 18 is plastered with cement, the grooves 21 serving to help hold the plaster in position as well as to hold the packing on the joint, the said packing and the plaster being united together.

10 It will be seen that when said sections are bolted together the cement may be securely held in place and cannot work loose by temperature changes.

The top ends of the legs 11 are connected 15 by the head portion 12, which is clearly shown in section in Figure 3. The lower portion of each of the heads is of a width equal to the full width of the legs 11, while its lower portion is provided with a downwardly extending portion 22 which is for 20 the same purpose as the members 15 and 17, before referred to.

Each of the front and back plates of the heads 12 is provided with an opening 23, 25 the opening of the front plate being formed in an outwardly extending conical flange 24, while the opposite head plate is provided with an inwardly extending conical flange 25, the said flanges being so arranged that 30 when the sections are adjacent to each other, the flange 24 of one will rest in the flange 25. These flanges are cast integral in section and require no machine work.

By means of my improved method of 35 constructing these conical flanges, I have materially reduced the cost of manufacture and according to my improved method, I chill the engaging surfaces of these conical flanges during the casting process, and this 40 is done by inserting in the hole at the proper places, smooth metal chills in positions where they are engaged by the molten metal as soon as it is poured into the mold. In this manner the coating surfaces of these 45 conical members are made relatively smooth and hard, and after the casting has been formed no machine work is required when they are used in connection with the soft metal washers, as hereinafter more fully described.

This chilling process is of itself old and well known and needs no further detail description here, but by applying the old process of chilling certain parts of the casting 55 I have produced a heater section which may be constructed more cheaply and just as efficiently as though the conical flanges were carefully and accurately machined after being cast.

60 In order to make an absolute tight fit between the two sets of flanges, I have provided a metallic washer 26, this washer being formed of a comparatively soft material and formed less conical than the 65 flanges. In fact, by using certain soft ma-

terials, the washer might be formed flat. As two sections are placed together, a washer is placed between the coating flange members. As the sections and flanges are drawn together by means of bolts 27, the washers 70 will assume substantially the shape of the flanges, and in such a manner that a tight joint is formed. Thus it will be seen that any unevenness in the surface of the flanges will be taken care of by the yielding washer 75 member.

The lower end of each of the legs 11 is provided with a substantially enlarged rectangular portion 27 of a width equal to the width of the leg. Each of the members 27 is formed hollow, and its forward and back plate each provided with an opening 28, one of the front and back plate members having an outwardly extending conical flange, while the other of the front and back plate members is provided with an inwardly extending conical flange, indicated by the numeral 29, and similar to the flanges 24 and 25, and each provided with a washer 85 similar to the washers 26.

The top face of each of the members 27 is inclined downwardly and inwardly to form a shoulder on which the fuel of the fire box rests. The operation and construction of this is similar to my previous patents. I have, however, provided means whereby a different grate construction may be employed.

The lower and inner edges of each of the members 27 are provided with an inwardly projecting lug 30 which is designed to receive one member of a set of grate bars 31.

The lower side of each of the members 27 is provided with a downwardly extending flange 32 of a width equal to the width of the leg 11. Each of the members 32 is provided at one edge with an outwardly extending flange 33, clearly shown in Figures 1 and 4, the outer edge of each of the flanges 33 being provided with an outwardly extending flange 34, the said flange 34 extending downwardly and inwardly from the lower edge of the member 27, the upper edge of the flange 32 being provided with an inwardly extending lug 35 spaced a slight distance below the lower edge of the member 27. These lugs 35 provide means on which the grate member 36 may be mounted, the said grate member being of a length slightly greater than one-half the length of the fire box. The grate 31, or the upper one, being preferably mounted in the back end of the fire box while the grate member 36 is mounted in the forward end of the fire box.

By this arrangement it will be seen that 125 the forward grate members 36 may be moved rearwardly beneath the grate member 31 and permit the ashes and cinders from the front end of the fire box to fall into said ash pit formed between the members 32 and 130

below the said grate member, thereby providing means whereby the cinders may be easily and quickly removed from the grates.

It often happens that it is desirable to do this while a small portion of the fire is still in the furnace. This may be accomplished by raking the coals under the back grate bar 31 before sliding the grate bar 36 rearwardly, then any cinders that may be under the said fuel and on top of the grate bar 31 may be raked forwardly from beneath said coals. Or, if it is desired, the ashes may be dumped into the rear end of the ash pit by a reverse operation of the grates.

15 The lower ends of the legs 11 are held in engagement with each other by means of bolts 37 extended through suitable openings in the flanges 33. The heads 12 are provided with upwardly extending flanges 38 to receive the bolts 27^a.

By forming the legs 11 hollow, a water chamber is provided therein, the lower end of which is in communication with the openings 28, the upper end of which is in communication with the chamber in the heads 12, the said chamber being in communication with the openings 23, the hollow portion or chamber of the members 15 being in communication with the chambers of the legs 11.

30 By this arrangement it will be seen that when a number of the sections have been secured together, all of the sections are in communication with each other. The said chambers may be operatively connected and placed in communication with each of the water or steam circulating systems illustrated in my previous patents.

It will be seen that I have provided sections of simple, durable and inexpensive construction which may be easily and quickly placed in position relative to each other, and when so placed tight joints will be provided between the water compartments of the various sections and between the flanges of the fire box and combustion chamber, the entire outer surface of the sections being plastered with heat-resisting cement which will close the joints between the heads 12, the plaster being forced into the space between the flanges 33 and behind the flanges 34 which

will close the joints of the fire box. The flanges 34 serve to assist in holding the plaster in position.

I claim as my invention:

1. In a furnace, the combination of a series 55 of independent detachable sections, each section being formed with an outer wall member and with a hollow fluid circulating member projected inwardly from the outer wall, one vertical edge of each outer wall member 60 being formed with a laterally extending flange substantially parallel with the wall member, and the other edge of the wall member being formed with a flange inclined inwardly, said parts being so arranged and 65 proportioned that when two adjacent sections are assembled the inwardly extended flange of one section will extend beyond the inner face of the straight flange of the adjacent section and to a point adjacent to the 70 inwardly extended hollow member of said adjacent section, and whereby there will be formed between said straight flange and said inclined flange and the adjacent portion of the hollow body a substantially triangular 75 opening, and a cement material placed in said opening, whereby in the event that the said cement material should for any reason become loosened from the surfaces with which it is in contact it cannot drop out of 80 the said opening in which it was formed.

2. A section for heaters comprising upright parallel leg members spaced apart, a head member connected with the upper ends of said leg members, said head member and 85 the upper portion of said leg member being formed hollow, the lower end of each of said leg members being provided with a downwardly projecting flange of a width equal to the width of said leg member, said downwardly projecting flange having an inwardly projecting lug to provide a rest for a grate member, each of said downwardly projecting flanges being also provided with a laterally 90 extending flange, and each of said laterally extending flanges being provided with a flange substantially parallel and opposite to the downwardly projecting flange. 95

CHARLES PHELPS.
